UNITED STATES PATENT OFFICE.

EDMUND C. MORGAN, OF NEW YORK, N. Y.; OLIVE EUGENIE MORGAN EXECUTRIX
OF SAID EDMUND C. MORGAN, DECEASED.

DRILLING APPARATUS.

Application filed September 22, 1922, Serial No. 589,816. Renewed March 23, 1927.

The object of this invention is to provide a drilling apparatus which shall be of improved construction and more efficient, economical and convenient in operation than devices of similar type previously known.

The invention is exemplified in the combination and arrangement of parts shown in the accompanying drawings and described in the following specification, and it is more particularly pointed out in the appended claims.

The present invention relates particularly to drilling apparatus mounted on a truck and adapted to travel on a mine track.

This application is a continuation in part of my co-pending application, Serial No. 196,294, filed October 12, 1917, for an improvement in mining machines.

In the accompanying drawings—

Fig. 1 is an elevational view of the complete mining machine with the drilling mechanism shown broken apart to indicate that it may be extended any desired distance beyond the forward end of the truck;

Fig. 2 is a plan view of the construction shown in Fig. 1;

Fig. 3 is a sectional elevational view of one of the drills taken on the line 3 of Fig. 2 looking in the direction of the arrow;

Fig. 4 is a sectional plan view of the drilling mechanism detached from the truck, the sections being taken on the line indicated at 4 in Fig. 3;

Fig. 5 is a fragmentary side elevation with parts in section showing the automatic trip for the drill;

Fig. 6 is a vertical sectional view on the line 6—6 of Fig. 5;

Fig. 7 is a vertical sectional view on the line 7—7 of Fig. 6;

Fig. 8 is a detail of construction;

Fig. 9 is a sectional view taken on the line 9—9 of Fig. 8;

Fig. 10 is a perspective view showing a detail of construction;

Fig. 11 is a sectional elevational view of the brake mechanism for anchoring the truck to the mine track;

Fig. 12 is a diagrammatic plan view showing the fan-shaped relation of the drilling mechanism operating at a mine heading of predetermined width; and

Fig. 13 is an elevational view showing diagrammatically the adjustment in inclina-

tion of the drilling mechanism relative to the truck and the mine track.

The machine constituting the embodiment of the invention shown in the drawings is carried upon a truck, the frame of which is shown at 1 in Fig. 1, and the wheels 2 of which are arranged to travel on a mine track comprising rails 3 of the usual form employed in the entries in rooms of a coal mine. Supported on the frame of the truck at the rear end thereof is a motor 4, the shaft 6 of which is connected by means of the worm gearing 7, 7 to the axles 8, 8 of the truck. By controlling the operation of the electric motor 4 the truck together with the drilling mechanism mounted thereon may be propelled in either direction along the mine track, particularly for transportation purposes, although if desired, the drills may be fed into the mine wall when held horizontally by moving the truck along the track. I prefer, however, to hold the truck stationary and feed the drilling mechanism relatively to the truck as hereinafter described.

In my aforesaid co-pending application, Serial No. 196,294, filed October 12, 1917, I have shown kerf-cutting mechanism in position to cut a kerf at the base of the mine wall in advance of the mine track of a width corresponding to the width of the mine heading, as illustrated in Fig. 12 of the accompanying drawings, but in the present application I have entirely omitted the undercutting kerf-cutter so that a separate machine may be used for undercutting a body of coal to be dislodged, either before or after the drilling apparatus hereinafter described has been operated to produce the drill holes illustrated in Figs. 12 and 13 of the accompanying drawings. It should be understood that these drill holes are for the purpose of receiving blasting charges to dislodge the coal from the vein at the mine heading corresponding approximately to the width of the previously prepared mine chamber.

The mechanism for drilling the blast holes is bolted to the upper rear portion of the truck or frame of the motor 4 and may be easily removed when desired. The drilling mechanism is mounted on a base plate 206 which is provided with a pair of upwardly projecting rings 207 in which hollow trunnions 208 of a housing 209 are journaled. The housing 209 is split along line 210, as

shown in Fig. 1, to allow access to the interior thereof, the parts being held together by bolts 211. A shaft 212 is journaled in the hollow trunnions 208 and carries a gear 213 which meshes with a pinion 214 driven by a motor 215 carried within the housing 209. At each end of the housing 209 and beyond the trunnions 208 there is located a bearing box 216 which forms an integral continuation of the trunnions 208. Located within these bearing boxes are beveled pinions 217 carried on the ends of the shaft 212 and arranged to mesh with beveled pinions 218 connected with the upper end of a sleeve 219 journalled on a bearing pin 220, as shown in Figs. 1 and 3. Journalled on the pin 220 above and below the sleeve 219 are members 221 and 222 which are secured to a bar 223, the three members thus connected together constituting a supporting frame for one of the drills and its operating mechanism.

A threaded feed screw 224 is journalled in the member 221 and is provided with a bevelled pinion 225 which meshes with the pinion 218. By this arrangement the guide bar 223 is provided with a universal joint connection which permits both vertical and lateral movement of the drill frame relative to the supporting plate 206, without disengaging the driving connection between the feed screw 224 and the drive shaft 212.

A central guide bar 226 may be rigidly connected with the housing 209 to swing vertically with the housing in the bearing rings 207, since no lateral movement of the central drill is necessary. The two end guide bars 223 and the central guide bar 226 may be supported by a leaf spring 227 secured to the base plate 206 by bolts 228 and to a lug 229 fastened to the central guide bar 226.

The entire housing 209 and the drills connected therewith may be swung vertically in the bearing rings 207 by a hand wheel 230 which engages the threads of a screw 231 passing loosely through an opening in an arm 232 connected with the housing 209 and pivoted at 233 to an arm 234 rigidly secured to the base plate 206, as shown in Figs. 1 and 2. The outer drill bars 223 may be swung horizontally by the hand wheels 235 connected with threaded members 236 which are pivoted to the outer bars 223 and the inner bar 226, respectively, as shown in Fig. 2.

The drills 237 are held at their inner ends in short shafts 238 provided with sockets 239 for the reception of the drills. The outer ends of the drills 237 are freely supported in openings 240 passing through blocks 241 secured to the outer ends of the guide bars 223 and 226 by screws 242. The blocks 241 are also provided with journal bearings for the outer ends of the feed screw 224. The short shaft 238 is journalled in a split block

243 and carries a gear 244 keyed to the shaft 238. The gear 244 meshes with a gear 245 also journalled in the split block 243 and having an elongated hub provided with a key 246 adapted to travel in a slot 247 which extends the entire length of the feed screw 224. By this arrangement the drill 237 is driven by the feed screw 224 independently of the position of the block 243 along the length of the feed screw. The blocks 243 are supported from the guide bars 223 and 226 by a dovetailed connection 299 best shown in Fig. 6. A housing 248 is secured to the front face of the block 243 by cap screws 249 and encloses a split nut comprising two parts 250 and 251 for engaging the threads on the feed screw, as best shown in Figs. 6 and 7. The blocks 250 and 251 which comprise parts of the split nut are mounted to slide vertically in the housing 248 and the lower block 250 has a shaft 252 journalled therein and provided with eccentric cams 253 at the outer ends thereof. Each of the cams 253 engages a link 254 which is pivotally connected at its opposite end to the upper block 251 of the split nut. It is apparent that rotation of the shaft 252 will move the blocks 250 and 251 toward and away from one another and into and out of engagement with the feed screw 224. One end of the shaft 252 carries a pinion 256 which is concentric with the shaft 252 and is free to rotate thereon and which has a pin 257 projecting outwardly from its face. The pin 257 is connected by a coil spring 258 with a pin 259 fixedly secured to the housing 248. The inner face of the pinion 256 carries a segmental lug 260 which engages a similar lug 261 projecting from the cam 253, as shown in Figs. 8 and 9. The tension of the spring 258 normally holds the lug 260 in the position shown in these views, and the lug 261 contacts with the lug 260 when the cams 253 are moved slightly past their central lower position in a direction to bring the lug 261 into engagement with the lug 260. In this way the blocks 250 and 251 are normally held in engagement with the feed screw 224 and any tendency of the blocks to spread apart is counteracted by the contact between the lugs 260 and 261. As shown in Figs. 5 and 6, a cylindrical rack bar 262 is slidably mounted in a projection 263 connected with the housing 248 and meshes with the gear 256. The rack bar 262 normally extends outwardly from the front face of the housing 248 when the split nut engages the feed screw 224.

During the operation of the drill the housing 248 and the split block 243 connected therewith are fed forwardly along the guide bar 223 by means of the split nut, and this operation continues until the end of the rack 262 comes into contact with the block 241 at the end of the guide bar. When this

occurs, further forward movement of the housing causes the rack bar 262 to rotate the gear 256 in a counter-clockwise direction, as viewed in Fig. 5. This rotation of the gear 256 will move the projection 260 arcuately away from the projection 261 which is on the cam 253, and the position of the cam and the split nut controlled thereby will not be affected until a half revolution of the gear 256 has been completed. Further rotation of the gear 256, however, will bring the pin 257 to which the spring 258 is connected past the dead center at the lower side of the gear and the spring will immediately complete the rotation of the gear and at the same time drive the rack 262 through its support 263 until it projects from the opposite side of the support an amount equal to the projection shown on the forward side of the support in Fig. 5. It is apparent by referring to Fig. 9 that at the beginning of the rotation of the gear 256 by the spring 258 the projection 260 on the shaft 252 will engage the projection 261 on the cam 253 but on the opposite side from that shown in this view, and that the rotation of the gear by this spring will bring the projection 261 to a vertical position above the shaft 252 and will also bring the cams 253 into positions above the axis of the shaft. This will spread apart the blocks 250 and 251 and disengage them from the feed screw 224. In this way quick release of the drill from the feed screw is effected at predetermined limits of travel of the drill. In other words, the drill is provided with automatic limit stopping mechanism.

After the drill has been released from the feed screw it may be returned to its original position by the drum and cable mechanism shown in Fig. 4. This mechanism comprises a drum 265 on which a number of cables 266 are wound, the cables being directed over pulleys 267 and having their ends secured to pins 268 connected with the split blocks 243. The drum 265 is controlled by a clutch 269 operated by a lever 270 (Fig. 2) carried on a shaft 271 which projects through the housing 209. By throwing in the clutch 269 after the drills have ceased to feed forwardly the cables 266 may be wound upon the drum 265 and the drills will thus be simultaneously returned to their initial positions. As the drills are brought into the rearmost positions, the rear ends of the rack bars 262 will engage the rear portion of the frame and thus be moved forwardly to reset the gears 256 and to reengage the split nuts with the feed screw 224, thus automatically setting the feeding device for a second operation. The motor for driving the drilling mechanism may be governed by a controller 272 mounted on the housing 209, as shown in Fig. 2.

The drilling operation is shown diagrammatically in Figs. 12 and 13 in which the positions of the drill frames are indicated by the reference letters *e*, *f*, and *g*. It will be seen from Fig. 13 that the drill frame is inclined upwardly out of parallelism with the mine track. It will be apparent that the truck cannot be moved upon the track while the drills are being operated in this position and it is therefore desirable to perform the drilling operations while the truck is being held stationary. In order to firmly secure the truck in stationary position on the track ordinary brakes may be applied to the wheels, but in order to prevent slipping of the wheels along the rails during the feeding of the drills I prefer to provide mechanism for gripping the rails, as shown in Fig. 11. By thus holding the truck stationary in a predetermined position the drills may be fed accurately in fan-shaped relation, as shown in Fig. 12, and also while inclined upwardly, as shown in Fig. 13. In other words, by securing the truck preliminarily in stationary position relative to the track the drills may be fed in perfect alignment with their axes as initially located.

The mechanism for securing the truck to the track to prevent slipping of the machine along the track during operation is shown in Fig. 11 and comprises a transverse shaft 300 journaled in bearings 301 on the truck frame 1 and provided with oppositely acting worms 302 which mesh with segmental worm gears 303 pivotally connected to the truck frame 1 and provided with brake arms 304 in position to engage the sides of the balls of the rail, as shown in Fig. 11. The opposite ends of the shaft 300 are provided with operating wheels 305. By actuating either of these wheels both of the rails 3 may be gripped by the two pairs of brake arms 304 so as to secure the truck rigidly connected to the mine track and prevent movement thereof in either direction along the track. If desired, one of the wheels 305 may be omitted and the coupling 306 relied on to transmit power to the worm gearing on both sides of the truck. When the coupling 306 is released, however, so that the sections of the shaft 300 operate separately, wheels 305 should be provided at both sides of the truck and in such event the brake arms 304 may be applied in pairs, one pair at one side of the truck and the other pair at the other side by operating the wheels 305 individually.

As shown in Fig. 1, a trolley pole 307 may be pivoted at 308 to the truck frame 1 and hooked at 309 to the motor frame 4 during the operation of the drilling mechanism. Or the trolley wheel 310 may be connected to a trolley wire in the mine chamber so as to furnish electric current to the electric motor 215.

4

during the operation of the drilling mechanism. It should be understood that after the truck has been secured to the track by means of the brake arms 304 the multiple drill may be adjusted in inclination on the axis of the shaft 212 by operating the wheel 230. Furthermore, by operating the wheels 235 the outer drills 237 may be varied in angular relation horizontally with the central drills 10 so as to secure the fan-shaped relation illustrated in Fig. 12. After the drills have been adjusted in inclination upwardly and laterally they are held securely in such adjusted position by the mechanism connected to the wheels 230 and 235. It should also be noted that each drill is fed longitudinally on its own axis while the housing 209 and the truck are held stationary.

Obviously those skilled in the art may 20 make various changes in the details and arrangement of parts without departing from the spirit and scope of my invention as defined by the claims hereto appended, and I wish therefore not to be restricted to the 25 precise construction herein disclosed.

Having thus fully described an embodiment of my invention, what I desire to secure by Letters Patent of the United States is:

30 1. In a mining machine, the combination with a drill, of a feed shaft for said drill, and a frame for supporting said drill and shaft parallel to each other, said frame having a protecting cover extending longitudinally along said feed shaft and over the same.

2. In a mining machine, the combination with a drill, of a feed screw for said drill, a frame extending longitudinally over said feed screw, and means connected to the rear end of said drill and movable along said feed screw under said frame for imparting forward feeding movement to said drill.

3. In a mining machine, the combination with a drill, of a feed screw for said drill, a frame extending along said feed screw to support the same, and means movable along said screw while guided along the bottom of said frame to feed the drill into the mine vein.

4. In a mining machine, the combination with a drill, of a feed screw for said drill, a frame having a flat cover plate for said feed screw, and feeding mechanism suspended from the bottom of said plate and guided along the same to advance said drill to extend forwardly from said frame and to retract said drill to a position where it will be substantially co-extensive with said feed screw.

5. In a mining machine, the combination with a drill, of a supporting frame therefor comprising a longitudinal cover plate, and means adapted to extend along said plate beneath the same for operating said drill.

6. In a mining machine, the combination with a drill, of a feed screw for said drill and of substantially the same length as said drill, spaced-apart bearings for said feed screw, an elongated frame extending over said feed screw and suspending said bearings at the end portions thereof, and means engaging said screw for feeding said drill while guided along the bottom of said elongated frame between said bearings. 75

7. In a mining machine, the combination with a drill, of a guide for said drill, a feed screw, an elongated frame covering said feed screw, bearings for said feed screw suspended from said frame, and means guided along the bottom of said frame for operating said drill including the feed thereof. 80

8. In a mining machine, the combination with a drill, of an elongated supporting frame for said drill, a feed screw mounted in bearings on said frame, a guide block, tongue and groove connections between said block and said frame to permit said block to have rectilinear movement along said frame, power transmission gearing on said block between said screw and said drill to rotate the latter, means on said block and threaded to said screw to effect feeding of the drill when said screw is rotated, and means for rotating said screw to operate the 95 drill. 90

9. In a mining machine, the combination with a drill, of a guide frame for supporting said drill, a feed screw on said frame, a guide block, a dove-tailed connection between said block and said frame, means mounted on said block and connected to both the feed screw and the drill for operating the latter including the feed thereof along 100 said frame and in advance thereof, and mechanism for driving said operating means. 105

10. In a mining machine, the combination with a drill, of a feed screw therefor, a supporting frame for said drill and screw to maintain the same in parallelism, a guide block slidable along said frame, means for rotating the drill upon rotating said screw, said means comprising a gear on said block splined to said screw to rotate therewith, a feed nut on said block and threaded to said screw, and means for rotating said feed screw to secure operation of said drill including feed thereof along its axis parallel to the axis of the feed screw. 110 115

11. In a mining machine, the combination with a plurality of spaced-apart drills, of a plurality of movable heads one connected with one end of each of said drills, a plurality of elongated guide frames one for each of said heads, a plurality of feed screws on each of which one of said heads is mounted, means mounted on each head for engaging its feed screw to cause the head to be guided along its frame and move its drill along its screw when the latter is rotated, 120 125 130

means carried by each of said heads to be driven by the respective screws for imparting rotary movements to said drills, and mechanism for operating the last-named 5 means from a single source of power.

12. In a mining machine, the combination with a plurality of separate and independent guide bars, of a plurality of feed screws one extending longitudinally along each of said 10 guide bars, each feed screw being in parallelism with the guide bar associated therewith, a plurality of heads one carried by each of said guide bars to slide respectively along the latter while guided thereby and while 15 engaging the feed screw associated therewith, means for engaging said screws for sliding the respective heads along said bars, drills respectively mounted in parallelism to said feed screws having one end supported 20 by the head associated therewith, gearing carried by each head for transmitting rotary movement from its associated feed screw to its respective drill in the various positions of said heads along said feed screws, means 25 associated with each head for operating the respective feed screws to slide the heads along said elongated guide bars and feed each drill parallel to its associated feed screw and to simultaneously rotate the respective 30 drill, and mechanism connected to all of said feed screws to rotate the same simultaneously and secure simultaneous rotation of the drills and simultaneous longitudinal feed thereof each along its respective guide bar.

13. In a mining machine, the combination with an elongated portable frame, of a supplemental frame pivoted thereto at the rear end thereof on a transverse axis, a tertiary frame pivoted to said supplemental frame 40 on an upright axis in position to extend along the top of said portable frame to the forward end thereof, a drill on said tertiary frame in position to extend longitudinally thereof and along the top of said portable frame to the forward end of the latter, and power transmission mechanism extending from said supplemental frame to said tertiary frame for operating the drill in its adjusted positions inclined upwardly and inclined laterally including the feed of said 45 drill longitudinally of said tertiary frame and beyond the forward end of said portable frame.

14. In a mining machine, the combination with a wheeled truck adapted to travel on a mine track, of a frame pivoted to said truck on a horizontal transverse axis, a plurality of elongated guide bars pivoted to said frame on upright axes, drills carried by said bars, and power transmission mechanism extending from said frame to said drills for operating the latter in their various adjusted positions of inclination upwardly and laterally.

15. In a mining machine, the combination

with a support, of an elongated drill guide mounted on said support, a drill guided through the forward end of said guide, means carried by said elongated guide and connected to the rear end of said drill for 70 rotating the latter and feeding the same along said guide while the drill is guided through the forward end of said guide, means for adjustably mounting said drill guide on said support, and driving connections extending from said support to said drill operating means to drive the latter for 75 the various positions of adjustment of said drill guide on said support.

16. In a mining machine, the combination 80 with a support, of a housing pivoted to said support, an elongated drill guide connected to said housing to move therewith, a drill under said guide, means under said guide for operating said drill, power transmission gearing within said housing and connected to said operating means, and a motor connected to power transmission gearing.

17. In a mining machine, the combination 85 with a support, of a frame pivoted thereto on a horizontal transverse axis, a plurality of elongated guide bars pivoted to said frame on upright axes, drills carried by said bars, and power transmission mechanism extending from said frame to said drills for 90 operating the latter in their various adjusted positions of inclination upwardly and laterally.

18. In a mining machine, the combination 100 with a support, of a frame journaled on said support, an elongated drill guide pivotally connected to said frame, a shaft mounted on said drill guide to be coextensive therewith, a stud shaft coaxial with said pivotal connection between said guide and said frame, 105 a drive shaft mounted on said frame, a drill mounted on said guide to be approximately coextensive therewith when said drill is in initial position and to reach out beyond said guide when fed along the latter, and bevel gearing connecting said shafts and arranged to form a power transmission chain operable in all positions of adjustment of said drill guide and housing.

19. In a mining machine, the combination 110 with a support, of a frame pivoted thereon for adjustment on a transverse axis, a plurality of elongated drill devices each comprising an elongated supporting frame, the outermost ones being pivoted to said frame for adjustment laterally on upright axes, a spring for sustaining a portion of the weight of said frames and drill devices, means for adjusting the inclination of said frames on said transverse axis, and means 115 for operating said drill devices from a common source of power in their adjusted positions.

20. In a mining machine, the combination 120 with a support, of a supporting frame hav-

ing an intermediate elongated drill support secured thereto, lateral elongated drill supports pivoted to said frame for adjustment on upright axes, a spring between said first-named support and said frame for counterbalancing the weight of the latter, means for adjusting the lateral drill supports on said upright axes, drill devices one on each of said elongated drill supports, and means for 10 operating said drill devices.

21. In a mining machine, the combination with a support, of a housing pivoted to said support for movement about a horizontal axis, a plurality of elongated drill guides, a 15 drill and a feed screw therefor mounted under each drill guide, a leaf spring connected to said support and arranged to counterbalance the weight of the drill guides, a motor on said housing, and means connected 20 between said motor and said feed screws for simultaneously operating said drills.

22. In a mining machine, the combination with a supporting frame, of a supplemental frame pivoted thereto transversely for adjustment on a horizontal transverse axis, a 25 plurality of elongated drills mounted on said supplemental frame to extend longitudinally of said supporting frame and for lateral adjustment relatively to each other, 30 means for spreading said drills relative to one another to adjust the positions thereof, means for tilting the said supplemental frame on said transverse axis to adjust the upward and downward inclinations of said 35 drills, and means for operating said drills.

23. In a mining machine, the combination with a support, of a drill frame carried by said support and having a plurality of drill guides thereon, all at substantially equal elevation, drills carried by said guides for operation at substantially equal elevation, means for shifting the guides in elevation in unison with one another while said substantially equal elevation is maintained, and 40 means for adjusting said guides laterally relative to one another to change the positions of said drills relative to said support.

24. In a mining machine, the combination with a drill, of mechanism for operating 45 said drill including feed thereof, means for automatically arresting the forward feeding movement of said drill, and means for quickly restoring said drill to initial position without rotating the same.

25. In a mining machine, the combination with a drill, of a guide for said drill, mechanism for feeding said drill along the guide, automatic limit stop mechanism for automatically discontinuing the feed of the drill 50 by rendering the feeding mechanism inoperative, and means for restoring said drill to initial position independently of said feeding mechanism and automatically restoring said feeding mechanism to operative condition 55 when said drill has been thus restored.

26. In a mining machine, the combination with a drill, of a guide for said drill, feeding mechanism for moving said drill along said guide, means for automatically disconnecting said drill from said feeding mechanism at a predetermined position in the movement of said drill along said guide, and mechanism for returning said drill along said guide to initial position independently of said feeding mechanism and then again 75 rendering operative the feeding mechanism.

27. In a mining machine, a drill supporting frame, a drill mounted to slide longitudinally along said frame, a feed screw for moving said drill relative to said frame, 80 means connected with said drill for engaging said screw, and mechanism for automatically disconnecting said screw-engaging means from said feed screw when said drill has reached its forward limit of movement. 85

28. In a mining machine, a drill, a frame for supporting said drill, mechanism for feeding said drill along said frame, means for automatically disconnecting said drill from said feeding mechanism when said 90 drill has reached one extremity of its movement, and for automatically reconnecting said drill with said feeding mechanism when said drill is returned to its initial position.

29. In a mining machine, the combination with a drill, of a guide therefor, means for feeding said drill along said guide, said means comprising a divided feed nut, and mechanism movable with said drill and arranged to engage a stop at one end of said 100 guide when said drill has reached one extremity of its movement to automatically spread apart the portions of said feed nut to disconnect the feeding mechanism from said drill.

30. In a mining machine, a drill, a supporting frame for said drill, means for moving said drill on said frame, mechanism for automatically disconnecting said moving means from said drill when said drill has 110 reached one extremity of its movement, and means for returning said drill bodily and rectilinearly to its original position.

31. In a mining machine, the combination with a frame, of a plurality of individual drills mounted thereon, means for simultaneously operating said drills including feed thereof, means for automatically disconnecting said feeding mechanism when said drills have reached the forward limits of travel, and means for simultaneously returning said drills quickly to their initial positions independently of said feeding mechanism.

32. In a mining machine, a drill, a guide bar on which said drill is mounted for longitudinal movement, a screw for feeding said drill along said guide bar, means connected with said drill for engaging said screw, a stop located at one end of said guide 125 130

bar, means for engaging said stop to disconnect said screw-engaging means when said drill has reached one extremity of its movement, means for returning said drill to its initial position, and means for reengaging said screw-engaging means when said drill has been returned to its initial position.

33. In a mining machine, a drill, a screw for feeding said drill, a threaded member connected with said drill for engaging said screw, and a spring controlled device arranged to be set by the movement of said drill for rapidly moving said screw-engaging means out of contact with said screw when said drill has reached a predetermined point along said guide.

34. In a mining machine, a drill, a guide for said drill, a screw for feeding said drill along said guide, a threaded member connected with said drill for engaging said screw, a shaft having a cam thereon for moving said threaded member into and out of engagement with said screw, a spring controlled pinion for operating said cam, and means arranged to rotate said pinion against the tension of said spring at a predetermined position in the movement of said drill along said frame, and to bring said pinion into a position to be rotated by the tension of said spring to operate said cam and disconnect said threaded member from said screw.

35. In a mining machine, the combination with a supporting frame, of a plurality of drilling units mounted thereon each for operation at approximately the same elevation and all supported entirely by said frame during operation, means for adjusting said units by spreading the same in fan-shaped relation across the mine wall in a general horizontal direction, and self-acting power-operated mechanism for simultaneously operating said drilling units including the feed of each drill along its own axis while said drilling units are supported entirely by said frame.

36. In a mining machine, the combination with a supporting frame, of a plurality of separate and independent drilling units mounted thereon for sole support thereby, means for spreading the drilling units in fan-shaped relation in plan, means for adjusting the drilling units in inclination and elevation, and mechanism for simultaneously operating said separate and independent drilling units including the automatic feed of each drill along its own axis while said drilling units are supported entirely by said frame.

37. In a mining machine, the combination with a supporting frame, of a plurality of drilling units mounted on the rear end portion of said frame to extend longitudinally over and along said frame for operation on an upright mine wall in advance of said

frame while supported entirely by the latter while the space in advance of said frame remains free and unobstructed, and means for operating such drilling units simultaneously including the automatic feed of each 70 drill.

38. In a mining machine, the combination with a supporting frame, of a plurality of separate and independent drill frames each elongated and each rigidly connected to said supporting frame in adjusted relation thereto and for sole support thereby, a plurality of drills one on each drill frame, means for adjusting the drill frames and drills in angular relation laterally, means for simultaneously adjusting the drill frames to secure simultaneous adjustment with the drills in elevation as a set, and means for operating the drills including individual feed thereof while in adjusted position relative to said frame and while supported solely thereby.

39. In a mining machine, the combination with a truck adapted to travel on a mine track, of an elongated drill frame pivoted on a horizontal axis to the rear end portion 90 of said truck to adapt the machine for operation in a low roof mine chamber when said drill frame is approximately horizontal and extending along the top of said truck, drilling mechanism extending from the rear end of said drill frame along the latter to the outer end thereof, and means on said truck for operating said drilling mechanism in a general horizontal direction approximately along the plane of the roof of the 100 mine chamber.

40. In a mining machine, the combination with a truck adapted to travel on a mine track, of a plurality of drilling devices mounted on top of the truck to extend longitudinally thereof with the space above said drilling devices and the space in advance thereof as well as the space in advance of the truck free and unobstructed, means for adjusting the drilling devices laterally in 105 fan-shaped relation and upwardly in inclination, and self-acting power-operated mechanism for simultaneously operating said drilling devices including automatic feed thereof individually each on its own 110 axis while supported solely by said truck.

41. In a mining machine, the combination with a supporting frame, of a plurality of drills mounted thereon for sole support thereby and spread across the mine wall in 120 a general horizontal direction at substantially equal elevation, the space in advance of said drills and in advance of said supporting frame being free and unobstructed, means for spreading the drills in fan-shaped relation across the mine wall, means for simultaneously adjusting the said drills in inclination and elevation while maintaining equal elevation, and means for operating said drills including the feed of each along 125 130

its own axis while supported entirely by said supporting frame.

42. In a mining machine, the combination with a drill, of feeding means therefor, limit stop mechanism comprising a split nut and means for holding the split portions of said nut spread apart, means for restoring the drill to initial position while the nut portions are spread apart, and means for automatically restoring the feeding means to operative condition upon the return of said drill to initial position.

43. In a mining machine, the combination with a drill, of feeding mechanism therefor comprising a split nut, limit stop mechanism comprising a rack and pinion connected to an eccentric for spreading apart the portions of said split nut, a spring and stops to hold said portions spread apart, and means for restoring the drill to initial position while said portions are spread apart and for automatically restoring said nut to feeding condition.

44. In a mining machine, the combination with a drill, of means for supporting the drill for operation in a general horizontal direction, means for operating the drill including the feed thereof, automatic limit stop mechanism for said operating means to automatically limit the outward feeding movement of said drill, and rope gearing for quickly restoring said drill by a movement in a general horizontal direction to initial position.

45. In a mining machine, the combination with a drill, of means for operating the same including the feed thereof, said operating means comprising a feed screw, automatic limit stop mechanism for rendering the feed along said feed screw inoperative at a predetermined limit of travel of said drill, and self-acting power-operated mechanism for quickly restoring the drill to initial position and automatically rendering the feed operative again in connection with said feed screw when the drill is thus restored.

46. In a mining machine, the combination with a drill, of means for operating the same including the feed thereof, automatic limit stop mechanism for rendering the feed inoperative at a predetermined limit of travel of said drill, manually controlled rope gearing for quickly restoring the drill to initial position, and automatic mechanism for restoring the operating means when said drill reaches its initial position.

47. In a mining machine, the combination with a wheeled truck adapted to travel on a mine track to a position near a mine heading, of a frame pivoted to said truck for adjustment relatively thereto on a horizontal axis, a plurality of elongated drills mounted on said frame for lateral adjustment relative to each other and adapted to reach forward beyond the forward end of

said truck for operation in said mine heading while the space in advance of said truck remains free and unobstructed, means for spreading the drills relative to one another to adjust the positions thereof, means for tilting said frame on said horizontal axis to adjust the upward and downward inclinations of said drills simultaneously while the space in advance thereof remains free and unobstructed, and means for simultaneously operating said drills including the automatic feed thereof.

48. In a mining machine, the combination with a drill, of a guide for said drill, means comprising a feed screw and split nuts associated with said feed screw for feeding said drill along said guide, means for automatically rendering the feeding mechanism inoperative by disconnecting said split nuts from said feed screw at a predetermined limit of travel of said drill, and mechanism comprising a rope for quickly returning the split nuts together with said drill in a straight line movement to initial position and automatically re-connecting said split nuts to said feed screw.

49. In a mining machine, the combination with a wheeled truck adapted to travel on a mine track to a position near a mine heading, of a plurality of spaced-apart drills mounted on said truck to operate in a general horizontal direction by reaching forward beyond the truck for operation on said mine heading, self-acting power-operated mechanism for operating said drills simultaneously including the simultaneous feed thereof into the mine heading, mechanism for automatically discontinuing the feed of the drills when the latter have reached predetermined forward limits of movement, and power-operated means comprising a plurality of ropes one connected to each of said operating mechanisms for simultaneously restoring the drills to initial positions and with a quick straight line movement to its retracted position relative to the truck.

50. In a mining machine, the combination with a supporting frame, of a motor on said frame, a plurality of drills, means for supporting said drills solely on said frame and in folded relation at the sides of said motor in a relatively low position to adapt the machine for transportation along a mine chamber having a relatively low roof, mechanism adapting said drills to independent adjustment to various angular positions relative to the path of travel of said supporting frame, and means connected between said motor and said drills for operating the latter in their various adjusted positions.

51. In a mining machine, the combination with a portable supporting frame adapted to move along a mine chamber having a low roof, of a plurality of drills extending along the upper portion of said frame and carried

thereby for transportation bodily therewith in a low position to clear the roof of said low roof mine chamber, means for permanently supporting said drills entirely on said

- 5 frame in readiness for operation, said means including mechanism for adjusting the drills independently of each other to operate on an upright mine wall from the said supporting frame as soon as the latter has been 10 transported into position for operation of the drills at the mine wall, means for effecting the driving of said drills simultaneously from a single source of power, and means for effecting the feeding of each drill along 15 its own longitudinal axis while said supporting frame remains stationary.

52. In a mining machine, the combination with an elongated supporting frame relatively low in height to adapt the same for 20 movement along a low roof mine chamber, of a plurality of elongated drills permanently supported on said frame both for transportation and for operation, means for supporting said drills at the sides of said 25 frame to occupy their lowest positions during transportation along such low roof mine chamber, means for supporting said drills for swinging adjustments vertically and horizontally independently of one another, 30 mechanism on said frame for each drill to hold the same in the position to which it is moved vertically and horizontally, and means for operating said drills including the feed of each on its own axis from the 35 supporting frame while the latter continues to support the drills and while said supporting frame remains stationary.

53. In a mining machine, the combination with a portable supporting frame, of a 40 bracket mounted on said frame for independent vertical and horizontal pivotal movement relatively thereto, a drill carried by said bracket during transportation in a low position to clear low roofs of mine chambers and for adjustment in inclination up- 45 wardly and downwardly and laterally relatively to said frame while supported entirely thereby, means for holding said bracket in its various positions of pivotal adjustment to 50 predetermine the operating axis of the drill, and means for rotating and feeding said drills at all positions of adjustment thereof while supported entirely by said bracket and said frame and while the latter 55 is relatively stationary during operation of the drills.

54. In a mining machine, the combination with a wheel-supported frame adapted to 60 travel along a mine track to a mine heading in a mine chamber, of a motor mounted on said frame, drills mounted permanently on said frame for sole support thereby during transportation and during operation, means for supporting the drills at the sides of the 65 motor in low positions during transporta-

tion to clear low roofs of mine chambers, means for supporting the drills solely on said frame for independent adjustment to various angular positions relative to the path of travel of said supporting frame, and 70 means for operating the drills from said motor while the drills are supported entirely by said frame and while the latter remains stationary thereby affording self-contained mechanism for operating said drills from 75 the adjusted stationary position of the frame adjacent the mine heading.

55. In mining apparatus, the combination with a supporting frame, of wheels for supporting the same for travel on a mine track, 80 a motor, a plurality of drills arranged on opposite sides of the motor, means for mounting said drills on said frame for adjustment independently of each other on horizontal and vertical axes, operating mech- 85anism for the drills including independent feed along each drill axis, and driving connections between the motor and said operating mechanism, said driving connections comprising a shaft on the horizontal axis 90 of adjustment of the drills below a plane extending through the upper edges of said wheels so that during transportation said drills may occupy low positions at the sides of the motor to clear low roofs of 95 mine chambers.

56. In a mining machine, the combination with a supporting frame adapted to enter a low-roof mine chamber, of a plurality of 100 brackets mounted on the rear portion of said frame for vertical and horizontal pivotal movement relatively thereto independently of one another, drills carried by said bracket and occupying positions extending longitudinally of said frame during transportation 105 thereof, means for rotating said drills at all positions of adjustments of said brackets, and means for feeding said drills longitudinally relatively to said brackets while said frame remains stationary.

57. A mining machine comprising a portable supporting frame adapted to move along a low-roof mine chamber, brackets carried by the sides of said frame at the rear end thereof, drills carried by said 115 brackets to extend longitudinally along said frame near the sides thereof to occupy low positions during transportation of the machine, means coating with said brackets to support said drills for independent adjust- 120 ment in inclination both laterally and vertically and so that said drills will not interfere with one another when swung on their pivotal supports, and means for simultaneously operating said drills including rotation of each and the feed of each along its own axis while said frame remains stationary.

58. In a mining machine, the combination with a portable supporting frame, of an 130

- operating motor carried by said frame, two pairs of drills, means for mounting one pair of drills at one side of said motor to extend along one side of said frame, means 5 for mounting the other pair of drills at the other side of said motor to extend along the other side of said frame, both of said mounting means being such as to permit adjustment of each drill in inclination both laterally and upwardly independently of the other drill and so that one drill of each 10 pair will occupy a lower position than the

other drill corresponding thereto in the respective pairs and while said drills extend horizontally and longitudinally along the 15 side of said frame in folded relation thereto during transportation, and means for operating said drills simultaneously including the feed of each along its respective axis.

In testimony whereof I have signed my 20 name to this specification on this 19th day of September, A. D. 1922.

EDMUND C. MORGAN.
